(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is the front view of a display screen or portion thereof with graphical user interface, showing my new design.

Broken lines shown in the FIGURE illustrate a display screen or portion thereof, and form no part of the claimed design.

All other broken lines shown in the FIGURE illustrate portions of a graphical user interface that form no part of the claimed design.

**1 Claim, 1 Drawing Sheet
(1 of 1 Drawing Sheet(s) Filed in Color)**
